A. J. Beaton INVENTOR.

BY

Frank L. Hinckley ATTORNEY.

UNITED STATES PATENT OFFICE.

ALLAN J. BEATON, OF NEW BRITAIN, CONNECTICUT, ASSIGNOR TO THE A. J. BEATON MANUFACTURING COMPANY, OF NEW BRITAIN, CONNECTICUT, A CORPORATION OF CONNECTICUT.

FLOOR OR CEILING PLATE.

1,344,219.

Specification of Letters Patent. Patented June 22, 1920.

Application filed April 6, 1920. Serial No. 371,591.

To all whom it may concern:

Be it known that I, ALLAN J. BEATON, a citizen of the United States, residing at New Britain, in the county of Hartford and State 5 of Connecticut, have invented certain new and useful Improvements in Floor or Ceiling Plates, of which the following is a specification.

This invention relates to floor or ceiling 10 plates, among the objects of the invention being the provision of a device of this kind which can be inexpensively and easily made and which possesses the requisite strength.

In the drawings accompanying and forming 15 part of the present specification I have shown in detail a form of embodiment of the invention which to enable those skilled in the art to practise the same will be set forth fully in the following description. I 20 am not restricted to this disclosure; I may depart therefrom in several respects within the scope of the invention defined by the claim following said description.

Referring to said drawings:

25 Figure 1 is a bottom plan view of a floor or ceiling plate involving the invention and showing the same open.

Fig. 2 is an edge view of the section, shown on the right in Fig. 1.

30 Fig. 3 is an elevation as seen from the outside of the front end portion of the other section.

Like characters refer to like parts throughout the several views.

35 The device may be employed in various ways although as will be inferred from the title, it generally fits against a floor or ceiling, and is intended to surround a pipe passing through such a floor or ceiling. It 40 comprises two body members as 2 and 3 in the form usually of half rings each having inner and outer flanges or lips as 4 and 5. When the plate is closed the ends of the respective flanges or lips 4 and 5 abut substantially against each other. The member 2 has fitted against it an approximately semi-circular strip 6 the member 3 having fitted against it a practically similar strip 7, the

respective strips edgewise engaging the parts 2 and 3. These strips 6 and 7 between their 50 ends have outward bows 8, and at opposite sides of their bows they fit substantially against the respective flanges 4 and are held thereto as by lugs or ears 9 integral with the said flanges 4 and bent over the upper 55 edge portions of the semi-circular strips to hold the latter solidly against the respective flanges.

The strips 6 are furnished at their rear ends with off-sets 10 fitted flatwise against 60 each other and pivoted together as by a rivet 11 so that the sections 2 and 3 can be opened and closed practically in the manner shown in Letters Patent No. 1,185,580 granted to me May 30, 1916 and to which reference 65 may be had. As a matter of fact the present device is a striking improvement of that shown in the patent.

The forward end portion of the semi-circular strip 6 shown on the left or that associated with the member 2 is provided with a lateral hook 12, to engage a catch portion 13 on the companion strip 7 when the plate is closed practically after the fashion shown in the Letters Patent identified. 75

The flanges 4 are slotted to receive the legs or branches of bowed springs 14 the free ends of which engage against the pipe around which the plate fits, the heads or outer portions of the two bowed springs 14 80 being disposed within the bows 8. Obviously the lugs 9 by which the strips 7 are held in place constitute one of the important features of the invention, the other being naturally the bows 8 which receive the 85 head portions of the springs 14. While the flanges 4 desirably are furnished with lugs 9 this may not always be necessary.

What I claim is:

A floor or ceiling plate comprising two 90 segmental body members coöoperative to form a ring, each of the body members having a flange along its inner edge, approximately semi-circular strips fitted edgewise against the body member and engaging the 95 flanges, the latter having integral ears bent

over the semi-circular strips to hold the same in place and said semi-circular strips being hinged together, the strips being outwardly bowed between their ends the lugs 5 being situated at opposite sides of the respective bowed portions, and bowed springs the bowed portions of which are situated within the other bows, the legs of the bowed

springs extending through slots in the flanges.

10

In testimony whereof I affix my signature in the presence of two witnesses.

ALLAN J. BEATON.

Witnesses:

BERTHA A. MACRISTY,
ALBERT F. ROUTHIER.
